COILING BLOCK

Albert G. Blodgett, Worcester, Mass., assignor to
 Morgan Construction Company, Worcester,
 Mass., a corporation of Massachusetts

Application February 20, 1942, Serial No. 431,663

8 Claims. (Cl. 242—78)

This invention relates to coiling blocks, and more particularly to the construction of rotatable blocks of the type used in forming flat metal stock into hollow cylindrical coils.

It is a common practice to deliver metal strip from a rolling mill to a cylindrical drum or "block" which is supported and rotated by means of an overhung horizontal arbor. The strip is wound under tension on the block. When the coil has been completed, the block and coil are withdrawn axially from the arbor and "up-ended" to bring the axis of the block vertical. The coil is then subjected to a "spinning" action by bringing about a relative rotation between the block and the outer portion of the coil, this rotation being in the proper direction to loosen the convolutions of the coil, whereupon the block can be withdrawn axially from the coil. When the strip is wound under high tension, as is often desirable, it subjects the block to heavy compressive loads. If the block is made of sufficient thickness and otherwise constructed to withstand these loads, it will be so heavy that it cannot be handled manually, and a crane or other mechanical apparatus may be required to lift it out of the spun coil. Furthermore, when a thick wall cylinder is subjected to an external radial compressive load, as by the winding of strip thereon under tension, the maximum tangential stress occurs in the fibers adjacent the bore of the cylinder, and the stress in the other fibers is progressively less as the outer surface of the cylinder is approached. Since it is the maximum stress which determines the maximum permissible loading, it is apparent that such a construction results in an inefficient utilization of the metal.

A further disadvantage inherent in prior blocks resides in the fact that as the wall of the block is made thicker in order to carry the load safely, the deformation or contraction of the block resulting from the load becomes less, and this decrease in the deformation actually results in a far greater load on the block when the coil is completed. In other words, the more the block yields during the formation of the coil, the less the pressure will be on the outside of the block, since the inner convolutions of the coil will to a considerable extent resist and support the radially inward pressure of the outer convolutions. This will be obvious when it is realized that a coil can be wound tightly upon a block of the well-known collapsible type, and upon completion of the coil the block can be collapsed leaving the coil entirely self-supporting, with all pressure removed from the block. Nor is this reduction of pressure resulting from deformation of the block a minor matter. In one particular instance calculations indicated that if the block were entirely incompressible the radial pressure thereon upon completion of the coil would be

12,000 lbs./sq. in., whereas if the radial deformation of the block during coil formation were .010" the radial pressure would be only 2000 lbs./sq. in.

It is accordingly one object of the invention to provide a block adapted for the winding of metal strip thereon at high tension without overloading of the block.

It is a further object of the invention to provide a block adapted for the winding of metal strip thereon and so constructed that it may be easily withdrawn from the coil after the latter has been spun.

It is a further object of the invention to provide a block adapted for the winding of metal strip thereon at high tension and so constructed that the stresses will be distributed much more uniformly throughout the block than with prior devices.

It is a further object of the invention to provide a block adapted for the winding of metal strip thereon at high tension and so constructed that it will yield radially, during the formation of the coil, to a considerably greater extent than blocks of prior construction utilizing substantially the same amount of material.

With these and other objects in view, as will be apparent to those skilled in the art, the invention resides in the combination of parts set forth in the specification and covered by the claims appended hereto.

Referring to the drawing illustrating one embodiment of the invention and in which like reference numerals indicate like parts,

Fig. 1 is a perspective view of a block and its supporting arbor, with the parts disassembled in the axial direction to show their construction to better advantage;

Fig. 2 is a perspective view of the invention in operation during the formation of a coil;

Fig. 3 is an enlarged section on the line 3—3 of Fig. 2; and

Fig. 4 is a sectional view showing the block and coil mounted on a spinning table.

The embodiment illustrated comprises a horizontal rotatable overhung arbor 10 which may be supported and driven by any suitable and well-known means. This arbor is preferably of square or other non-circular cross-section, and it serves as a supporting and driving means for the block which forms the subject matter of the present invention.

In accordance with the preferred form of the invention this block comprises a plurality of separable parts which can be assembled telescopically in the axial direction. The outermost of these parts is preferably shaped to provide a continuous smooth outer cylindrical surface about which the metal strip may be wound into a coil. Radial clearances are provided between the parts, and these clearances, while small, are neverthe-

less preferably greater than would be required merely to permit telescopic assembly. The arrangement is such that during the formation of the coil and the resultant application of radial compressive loading to the outermost part of the block, this part will receive all of this loading until it has been deformed enough to take up the radial clearance between itself and the next part, whereupon this next part will assume a portion of the load which is added thereafter. When the two outer parts have been deformed enough to take up the radial clearance which surrounds the third part (if one be provided), any subsequent loading will then be divided among all three parts of the block. Upon completion of the coil, if the block is correctly proportioned, the parts thereof will be stressed far more uniformly than would be the case with a single-piece block of the same thickness, and the radial deformation will be much greater than with a single-piece block. Furthermore, all stresses will be well within the elastic limit of the material, so that the original clearances will be restored when the loading is removed by the spinning of the coil, and the parts can easily be withdrawn one at a time from the coil. Since the weight of each individual part is much less than the weight of a single-piece block, the withdrawal is greatly facilitated.

In the particular embodiment illustrated the block is made in three pieces, including an inner member 11, an intermediate member 12, and an outer member 14. All three of these members are in the form of cylindrical sleeves. The inner member 11 is provided with internal ribs 15 shaped to provide a square bore or opening 16 adapted to fit the arbor 10 with ample clearance for easy withdrawal therefrom. This member 11 is shown slightly longer than the other sleeves, and at its outer end it is provided with an inwardly extending annular flange 18 which facilitates the up-ending of the loaded block, as will be explained hereinafter. At its other end the member 11 is provided with a pair of diametrically opposite radially projecting lugs 19 (one only being visible in Fig. 1). At assembly these lugs 19 enter notches 20 in the inner end of each sleeve 12 and 14 to provide a torque-transmitting connection between the parts of the block. In the case of blocks large enough to make weight reduction an important matter, I prefer to use a metal or metallic alloy of relatively low specific gravity and high strength. One such alloy is Duralumin, which contains 4.0% copper, .5% manganese, .5% magnesium, and the balance aluminum. This alloy when properly heat treated has an elastic limit of 40,000 lbs./sq. in., a Young's modulus of 10,000,000, and a Poisson's ratio of .33.

Radial clearances are provided between the intermediate member 12 and the members 11 and 14 respectively, these clearances depending upon the size and material of the block. By way of example, let us suppose that we are to construct a block with an outside diameter of 16 inches for the coiling of metal strip 9 inches wide at high tension. If such a block is made of three telescoping sleeves of Duralumin, each with a radial thickness of one inch, the weight of each sleeve will be small enough to permit easy handling thereof by one man. Since the ribs 15 have the effect of strengthening the inner sleeve 11, this sleeve can be somewhat less than one inch in thickness and still have the same strength as an unribbed sleeve one inch thick. To simplify,

the calculations, it will be assumed that the inner sleeve is one inch thick and without ribs.

Ordinarily, in calculating the deformation and stresses in hollow cylinders subjected to external radial pressure, the cylinder is treated as thin-walled if the ratio of thickness to outside diameter is less than 1/10, and as thick-walled if this ratio is greater than 1/10. Different formulas are applied in these two instances. In the present case, all three sleeves may be treated as thin-walled cylinders.

For thin-walled cylinders, we have the formula

$$(1) \quad D = \frac{RS}{E}$$

where

D = the radial deformation

R = the mean radius

S = the tangential stress

E = Young's modulus

Applying this formula to the outer sleeve 14, and assuming that this part is made of Duralumin and that 30,000 is a reasonable maximum tangential stress, we have

$$D = \frac{7.5 \times 30,000}{10,000,000} = .0225$$

Applying the same formula to the intermediate sleeve 12, we have

$$D = \frac{6.5 \times 30,000}{10,000,000} = .0195$$

Applying the same formula to the inner sleeve 11, we have

$$D = \frac{5.5 \times 30,000}{10,000,000} = .0165$$

From the above it will be seen that the outer sleeve can safely be reduced .0225" radially, the intermediate sleeve .0195", and the inner sleeve .0165". Accordingly, a radial clearance of .003" (.0225" - .0195") should be provided between the outer sleeve and the intermediate sleeve, and a radial clearance of .003" (.0195" - .0165") should be provided between the intermediate sleeve and the inner sleeve. With this construction, under conditions of maximum safe load, all the clearances will be taken up by elastic deformation, and the stresses in the several sleeves will be substantially uniform. Furthermore, the outside diameter of the block will be reduced .045" (2 $\times$ .0225").

These conditions are in marked contrast with those which would be encountered in a single-piece block utilizing the same amount of metal. Such a block would have an outside diameter of 16 inches, and a thickness of 3 inches. For a thick-walled cylinder of this type we have the formulas

$$(2) \quad D = P \frac{B}{E} \left(\frac{A^2 + B^2}{B^2 - A^2} + M \right)$$

and

$$(3) \quad P = S \left(\frac{B^2 - A^2}{2B^2} \right)$$

where

P = the applied radial pressure

A = inside radius

B = outside radius

M = Poisson's ratio, the other elements being as defined in connection with Formula 1.

Combining (2) and (3), we obtain

$$D = S \left(\frac{B^2 - A^2}{2B^2} \right) \frac{B}{E} \left(\frac{A^2 + B^2}{B^2 - A^2} + M \right)$$

Substituting the known values for the thick-walled Duralumin cylinder, using 30,000 as a reasonable maximum tangential stress, we find that

$$D=0.0143$$

Thus the single-piece block can be safely subjected to a radial deformation of only .0143", as compared with .0225" for the three-piece block.

In calculating the value of the radial pressure to which a thin-walled cylinder can be safely subjected, we have the formula

$$(4) \quad P = \frac{ST}{R}$$

where

T = the wall thickness, and the other elements are as set forth above.

Applying this formula to the inner sleeve 11, we obtain

$$P_{11} = \frac{30,000 \times 1}{5.5} = 5454$$

Applying the formula to the intermediate sleeve 12, we obtain

$$P_{12} = \frac{30,000 \times 1}{6.5} = 4615$$

Applying the formula to the outer sleeve 14, we obtain

$$P_{14} = \frac{30,000 \times 1}{7.5} = 4000$$

Under full load conditions, the clearances between the sleeves disappear, and the sleeves 11 and 12 serve to support the sleeves 12 and 14 respectively. Hence the strength of the multi-sleeve block is cumulative, and we have as the safe limit of external pressure for the assembled block

$$P = 5454 + 4615 + 4000 = 14,069$$

In calculating the value of the radial pressure to which a thick-walled cylinder can be safely subjected, we have Formula 3 set forth above. Applying this to a single block with an outside diameter of 16 inches and a thickness of 3 inches, we obtain

$$P = 30,000 \left(\frac{64 - 25}{2 \times 64} \right) = 9140$$

Thus the single piece block can be safely subjected to an external pressure of only 9140 lbs./sq. in., as compared with 14,069 lbs./sq. in. for the three-piece block, which fact alone would permit the winding of strip at a much higher tension on the three-piece block. However, this is by no means the entire story for, as we have already seen, the single piece block will contract only .0286" in diameter before it is fully loaded, whereas the three-piece block will contract .045" in diameter. This increased contraction or yielding has a very pronounced effect in reducing the pressure between the coil and the block, and therefore makes it possible to employ a still greater tension on the strip. For the same reasons, it will be clear that it is possible to wind strip at a given tension into a coil of much greater outside diameter with the three-piece block than with the single-piece block.

It will now be apparent that in the operation of the invention the telescopically-assembled block will be mounted on the arbor 10, which will be driven by suitable means. The lugs 19, by engagement with the notches 20, will cause the three parts of the block to rotate in unison. A coil C of strip metal will be wound under tension

on the outside of the sleeve 14 in known manner. Ordinarily, this metal will be delivered to the block from a rolling mill 22 (Fig. 2). As the formation of the coil proceeds, the radial pressure on the outside of the block will increase, forcing the outer sleeve 14 to contract against the intermediate sleeve 12, and eventually forcing the intermediate sleeve to contract, against the inner sleeve 11. When the coil is completed, the loaded block will be withdrawn from the arbor and up-ended, preferably by means of an apparatus 25 (Fig. 4) having fingers 26 adapted to engage the flange 18. For a complete disclosure of the apparatus 25 reference may be had to the patent to Eddy et al. No. 2,256,975, granted Sept. 23, 1941. This patented apparatus can be used to "spin" the coil and loosen the convolutions thereof, which will release all pressure from the sleeves 11, 12 and 14. Since these sleeves were not stressed beyond the elastic limit they will resume their original dimensions, the original clearances will be restored, and the sleeves can be lifted one at a time from the coil. Since each sleeve represents only a fraction of the entire weight of the block, this lifting is a comparatively easy matter. It will be understood that at least two blocks should be provided, so that one coil can be spun while the next coil is being wound.

Having thus described my invention, what I claim as new and desire to secure by Letters Patent is:

1. A rotatable coiling block comprising a metal inner member, a metal outer member surrounding the inner member with a slight radial clearance between said members, the outer member having a continuous smooth outer cylindrical surface about which metal strip may be wound under tension to form a coil, and means to transmit torque from one of said members to the other.

2. A rotatable coiling block comprising a metal inner member and a metal outer member surrounding the inner member with a slight radial clearance between said members, the outer member having a continuous smooth outer cylindrical surface about which metal strip may be wound under tension to form a coil, the members being so proportioned that as the outer member contracts by reason of the radial compression load applied thereto during the formation of the coil the said clearance will disappear before the outer member is stressed to its elastic limit in the tangential direction.

3. A rotatable coiling block comprising a metal inner member and a metal outer member surrounding the inner member to provide a continuous smooth outer cylindrical surface about which metal strip may be wound under tension to form a coil, there being a radial clearance between said members such that as the radial compression load applied to the outer member during the formation of the coil increases, the said clearance will disappear and both members will reach the safe limit of tangential compressive stress at substantially the same time.

4. A rotatable coiling block comprising a metal inner member and a metal outer member arranged to be assembled telescopically in the axial direction, the outer member having a continuous smooth outer cylindrical surface about which metal strip may be wound under tension to form a coil, there being a radial clearance between said members such that as the outer member contracts by reason of the radial com-

pression load applied thereto during the formation of the coil the said clearance will disappear before the outer member is stressed to its elastic limit in the tangential direction.

5. A rotatable coiling block comprising a plurality of cylindrical metal sleeves arranged to be assembled telescopically in the axial direction, the outer sleeve having a continuous smooth outer cylindrical surface about which metal strip may be wound under tension to form a coil, there being a radial clearance between the sleeves such that as the coil increases in diameter and applies an increased radial compression load to the block the clearance will disappear before any of the sleeves is over-stressed in the tangential direction.

6. A rotatable coiling block comprising at least three cylindrical metal sleeves arranged to be assembled telescopically in the axial direction, the outer sleeve having a continuous smooth outer cylindrical surface about which metal strip may be wound under tension to form a coil, there being radial clearances between adjacent sleeves such that as the coil increases in diameter and applies an increased radial compression load to the block the clearances will all disappear before any of the sleeves is over-stressed in the tangential direction.

7. A rotatable coiling block comprising a plurality of metal members arranged to be assembled telescopically in the axial direction and providing a continuous smooth outer cylindrical surface about which metal strip may be wound into a coil, the outer member having a notch in one end, and the inner member having a lug thereon which enters the notch at assembly to prevent relative rotation of the members.

8. A rotatable coiling block comprising a metal inner member, and a metal outer member in the form of a cylindrical sleeve surrounding the inner member with a slight radial clearance between said members, the outer member having a continuous smooth outer cylindrical surface about which metal strip may be wound under tension to form a coil, the thickness of the outer member being less than one tenth its outside diameter, and the members being so proportioned that as the outer member contracts by reason of the radial compression load applied thereto during the formation of the coil the said clearance will disappear before the outer member is stressed to its elastic limit in the tangential direction.
